UNITED STATES PATENT OFFICE.

WILLIAM C. O'BRIEN, OF BALTIMORE, MARYLAND, ASSIGNOR TO MONITOR MANUFACTURING COMPANY OF BALTIMORE CITY, OF BALTIMORE, MARYLAND, A CORPORATION OF MARYLAND.

ELECTRIC-MOTOR STARTER.

No. 900,035.

Specification of Letters Patent. Patented Sept. 29, 1908.

Original application filed October 23, 1905, Serial No. 284,105. Divided and this application filed September 10, 1906. Serial No. 333,987.

To all whom it may concern:

Be it known that I, WILLIAM C. O'BRIEN, a citizen of the United States, residing at Baltimore, in the State of Maryland, have 5 invented certain new and useful Improvements in Electric-Motor Starters, of which the following is a specification.

The purpose of this invention is to provide an automatic starter for electric motors 10 which will operate to cut out the starting resistance from the armature circuit as the motor acquires speed, without the use of dash pots or mechanical retarding devices, or sliding contacts.

15 This application is a division of my co-pending application, Serial No. 284,105, filed October 23rd, 1905.

In the accompanying drawing, Figure 1 is a view showing diagrammatically a starter 20 made according to my invention, the parts being shown in their normal positions in full lines, and the dotted lines indicating the manner in which the solenoid cores, which cut out the starting resistance, are released 25 from the mechanical holding means when the current is turned on; Fig. 2 is a similar view showing the positions of the parts after the current has been turned on and all of the resistance has been cut out except one section.

30 Referring to the drawings M indicates an electric motor and S indicates the line switch for connecting the starter and motor with the line circuit L L. The motor shown in the drawings is shunt wound, the field circuit extending from the line switch terminal 1 through conductor 2 and motor field f to the return wire 3 and thence to the line switch terminal 4. The armature circuit 5, as shown in the drawing, is connected to line 35 terminal 1 through conductor 2 and extends from said conductor successively through the coils b of a solenoid B, a section R of starting resistance, switch contact 6, the coil c of a solenoid C, a section R' of starting resistance, 40 switch contact 7, coils d of a solenoid D, a section R'' of starting resistance, switch contact 8, armature a and conductor 3 to the line terminal 4. The regulating solenoids B, C and D are vertically arranged so that their 45 cores 9, 10 and 11 will tend to drop by gravity towards the fixed contacts 6, 7 and 8, respectively arranged beneath the cores, and each core preferably has at its lower end a swiv-

eled section or shoe s for making good electrical contact with the fixed contact piece 55 beneath it when the core drops. The cores are connected by flexible conductors 12, 13 and 14, respectively, to the conductor 2 and by said conductor to the line terminal 1. The flexible conductors 12, 13 and 14 might 60 be connected directly to the shoes s, but for convenience they are connected to the rods 9^a, 10^a and 11^a respectively, of non-magnetic metal, which are secured to the upper ends of the cores, and the flexible conductors, 65 the rods and the cores form shunt circuits which short circuit the solenoid coils and the resistance steps when the cores are down and the shoes s rest upon the stationary contacts.

The cores constitute the movable members 70 of switches t, t' and t'', and the contacts 6, 7 and 8 are the opposing members of the switches. These switches are normally held in the open positions, shown in Fig. 1, by bell crank levers e, f and g, having their 75 longer arms hinged to a rod 15, and their shorter arms extending beneath collars 16, 17 and 18 upon the rods which project upwardly from the ends of the solenoid cores. The bell crank lever e has an extra arm 19 upon 80 which is suspended the core 20 of a holding solenoid H. The cores and the levers are so proportioned that the core 20 will overbalance the weight of the cores 9, 10 and 11, and for this purpose the core 20 may be weighted 85 at its lower end, as indicated at 20^a. The solenoid H, as shown in the drawing, has windings h connected to the line switch terminals 1 and 4 by conductors 21 and 22, so that each time the line switch is closed the core 20 90 will be instantly raised, and when the line switch is opened the core 20 will drop.

When the line switch is in open position, as shown in Fig. 1, the cores of solenoids B, C and D are held in their upper positions, 95 and as the switches t, t' and t'' are then open the windings of these solenoids and the resistance sections are all in series with the armature. The armature circuit, it will be noted, is never interrupted between the line 100 switch and the motor. As soon as the line switch is closed the solenoid H attracts its core, and thus the bell crank levers are at once thrown into the position shown in dotted lines in Fig. 1 and in full lines in Fig. 105 2; but the starting current in the armature

circuit will ordinarily be so great as to hold the cores of the solenoids B, C and D, in their upper positions after the supporting levers have been moved downward. These 5 solenoids are arranged so that their cores will drop in succession as the current in the armature circuit decreases. For this purpose I have shown the collar 16 heavier than the collar 17, and the latter heavier than the 10 collar 18, so that the cores of the solenoids are differently weighted and with similar windings the cores will drop in succession, from left to right in the drawing, as the current decreases by reason of the acceleration 15 of the motor armature, in starting. When the current falls to a certain predetermined extent, the core 9 drops, thus closing the switch t and the current then flows from the line terminal 1 and conductor 2 through 20 flexible conductor 12, core 9 and contact 6 to the conductor 5 and thence through the successive solenoids and resistance sections to the armature. The closing of the switch t , causes the coils of solenoid B and the resistance 25 section R to be short circuited. With a further decrease in the starting current the core of solenoid C will drop, closing the switch t' , and the current will then pass through flexible conductor 13, core 10 and 30 contact 7 to the conductor 5 and thence through solenoid D and resistance section R' to the motor. The coils of solenoid C and the section R' of the resistance will therefore be cut out. In Fig. 2 the parts are in their 35 position just described, the cores 9 and 10 being down and the core 11 still in its upper position. With a still further fall in the starting current, due to the acceleration of the armature, the core of solenoid D will drop 40 and short circuit its coils and the resistance section R', the current then passing through flexible conductor 14, core 11 and contact 8, and from thence through conductor 5 directly to the motor. All of the resistance 45 sections and the solenoid coils will then be cut out. This cutting out of the resistance sections takes place at a rate which is approximately proportional to the fall of current in the armature circuit and to the acceleration 50 of the armature. If the motor starts quickly the solenoid cores drop in succession quickly; but if the motor is heavily loaded and starts slowly the cores will be held longer in their upper positions.

55 When the line switch is opened, the solenoid H is thereby deenergized, and its core 20 drops downward, causing the bell crank levers to rock and lift the cores of the solenoids B, C and D, thus opening the switches t , t' and t'' and thereby reinserting the starting resistance and the solenoid windings in the armature circuit. These switches for opening and closing the shunt circuits around the resistance sections and solenoid coils, it will 60 be noted are operated in both directions by

gravity, the cores 9, 10 and 11 being raised by the weight of the core 20 when the current is cut off, and moving to their closed positions by their own weight when the mechanical supports are removed and the current in 70 the armature circuit falls to normal.

What I claim is—

1. In an automatic starter for electric motors, a starting resistance for the armature circuit, a regulating device having windings in said circuit and having a core or armature, a switch for cutting out said resistance, said switch being normally open and movable by said core or armature to closed position, electro-magnetic holding means having a 80 core or armature, and connections between said cores or armatures whereby the core or armature of the holding means serves as a means for normally overbalancing the core or armature of the regulating device to permit 85 the switch to remain open, said holding means being arranged to retract its core or armature when current is turned on.

2. In an automatic starter for electric motors, a starting resistance for the armature circuit, and a series of regulating devices each having windings in said circuit and each having a core or armature, switches for cutting out said resistance and windings, said switches being normally open and movable 90 by said cores or armatures to closed position, an electromagnetic holding device having a core or armature, and connections between said cores whereby the core or armature of the holding device serves as a means for normally overbalancing the cores or armatures of the several regulating devices to permit 95 the switches to remain open, said holding device being arranged to retract its core or armature when current is turned on.

3. In an automatic starter for electric motors, a starting resistance in the armature circuit, a regulating solenoid having windings in said circuit, a switch for short-circuiting said resistance and windings, said switch being connected to the core of said solenoid and movable therewith by gravity to closed position, a lever movable independently of said core and adapted to move said core to open the switch, and a holding solenoid having a core connected to said lever and adapted to overbalance the core of the regulating solenoid and hold said latter core with the switch in open position, said holding solenoid being adapted to move the lever so as to release the core of the regulating solenoid when the current is turned on.

4. In an automatic starter for electric motors, a starting resistance in the armature circuit, a plurality of regulating solenoids having windings in said circuit, switches for short-circuiting said resistance and windings, said switches being connected to the cores of said solenoids, and movable therewith by gravity to closed position, a lever 110

105

movable independently of said cores and means connected with the lever for moving said cores to open the switches, and a holding solenoid having a core connected to said lever and adapted to overbalance the cores of the regulating solenoids and hold said latter cores with the switches in open positions, said holding solenoid being adapted to move

the lever so as to release the cores of the regulating solenoids when current is turned on. 10

In testimony whereof I affix my signature, in presence of two witnesses.
